OR D 16,732

Design No. 16,732, dated June 8, 1886.

UNITED STATES PATENT OFFICE.

CANDACE WHEELER, OF NEW YORK, N. Y.

DESIGN FOR THE DECORATION OF CURTAIN FABRICS, &c.

SPECIFICATION forming part of Design No. 16,732, dated June 8, 1886.

Application filed April 28, 1886. Serial No. 200,483. Term of patent 7 years.

To all whom it may concern:

Be it known that I, CANDACE WHEELER, a citizen of the United States, residing in the city, county, and State of New York, have invented and produced a new and original Design for the Decoration of Curtains and Draperies for Walls, Ceilings, &c., of which the following is a specification, and which is illustrated in the accompanying drawing.

The design consists in a fabric having upon its surface the scroll-shaped figures A, each formed by a number of converging lines or scrolls, B, so as to make a whirl at the focus or point of convergence. The design thus formed is continued over the entire surface to be decorated therewith, and is interspersed

at intervals with the representations, C C, of crabs, lobsters, or like shell-fish.

I claim—

The design for curtains, draperies, and like fabrics, the same consisting of a curtain, drapery, or like fabric having upon its surface the representation of whirls A, each formed of a series of converging scrolls, B, and the interspersed conventionalized representations of shell-fish, C, substantially as described and shown.

CANDACE WHEELER.
